UNITED STATES PATENT OFFICE.

OTTO A. ROENSCH, OF NEWARK, NEW JERSEY.

X-RAY TUBE.

Application filed January 4, 1919. Serial No. 269,589.

To all whom it may concern:

Be it known that I, OTTO A. ROENSCH, last a subject of the Emperor of Germany, and a resident of Newark, Orange County, 5 State of New Jersey, have invented certain new and useful Improvements in X-Ray Tubes, set forth in the following specification.

The object of this invention is to prolong 10 the life of an X-ray tube particularly by shielding static electricity and lateral bombardment in the vicinity of the cathode. To the above ends employment is made of a tubular static shield of conducting material 15 mounted in a novel manner to increase its insulation and facility in mounting.

These objects will be better understood by reference to the following specification, 20 descriptive of an illustrative embodiment of the invention, which is shown for purposes of illustration only in the accompanying drawings, forming a part hereof, and in which like characters designate corresponding parts in the several figures. In the 25 drawings—

Fig. 1 is a side elevation of a preferred form of the invention;

Fig. 2 is a longitudinal vertical section with parts broken away and drawn to an 30 enlarged scale; and

Fig. 3 is a perspective view of the preferred embodiment of the static shield.

The X-ray tube A comprises the usual globular central portion 1, and desired adjuncts such as the vacuum regulator 2 and the auxiliary anode 3 and two alined tubular extensions forming a part of the hermetical closure. These are the anode extension B and the cathode extension C. An anode 4 35 of approved construction, preferably mounted on a hollow metallic stem 5 suitably fixed within the extension B, is provided.

The principal features of the invention are exemplified in the cathode structure.

40 The outer glass tube 6 has the usual end closure 7 through which the lead-in wire is sealed. Suitably attached, as by fusing at approximately the extreme end of the outer extension 6, is a double tubular support 9. Of this double support both the shield support 10 and the cathode support 11 are co-axial with the outer extension 6. They extend inwardly towards the globe 1. The cathode support is preferably provided with 45 the rear flange 12 sealed to the shield support 10 slightly inwardly from the seal 13

of the shield support. Both these supports are preferably imperforate and are fabricated from glass having high insulating value. These imperforate tubes effectively 60 shield the stem 18 against serving as a by-path for current flow in the tube, which is localized at the dish-shaped cathode proper 16.

The dish-shaped cathode proper 16 has a 65 cylindrical stem 17 into which is axially mounted a cylindrical conductor 18. The parts 16, 17 and 18 are preferably of aluminum, a split sleeve 19, preferably of steel being riveted to the stem 17, and then slipped 70 and sprung about the inner end of the glass support 11, in which manner a secure mounting is obtained, with no danger of local stresses.

The static shield D comprises a metal ring 75 20 of internal diameter slightly larger than the cathode cup 16, and less than that of the throat 24, and extending rearwardly into a gripping sleeve 21, preferably provided with slots 22 and 23 to facilitate an easy adjustment and mounting upon the support 10. It should be noted that the rim of the cathode 16 is much nearer to the rim of the shield 20 than is the rim of the shield 20 to the glass throat 24. This proportioning 80 of separation effectively shields the throat 24 as well as centralizes the cathode stream.

It should be noted that the static shield D, which in the operation of the tube acquires the same potential as the cathode 90 tending to centralize the cathode stream, is effectively insulated against conduction to the walls of the tube, and is effective in protecting the throat of the glass structure as at 24. It is preferable that the beam of the shield D be located at least twice as far from the portion 24 of extension C as it is from the cathode 16.

What I claim and desire to secure by 100 United States Letters Patent is:—

1. In an X-ray tube, in combination with its enclosing wall formed with a tubular extension forming the cathode stem and provided with an enclosure; a large co-axial tubular support of glass attached at its far end of said cathode stem at the end closure thereof; a second co-axial tubular stem of glass extending inwardly from and secured at its outer end directly to the walls of said first mentioned tubular stem and forming on its inner end a support for the cathode; and a shield supported out of contact with 105 110

- the cathode stem at the inner end of said first mentioned tubular stem.
2. In an X-ray tube, a lateral tubular extension of glass closed at its outer end; a double coaxial tubular support attached at its far end to the end of said extension at its said closed end and having an inner cathode supporting portion and an overlapping shield supporting portion; a cathode secured to the inner end of said cathode supporting portion; and a static shield surrounding said cathode out of contact therewith and mounted on the end of said shield supporting portion.
3. In an X-ray tube, the combination with its enclosing wall formed with a tubular extension forming the cathode stem, and a cathode located in said stem and extending at its head within the neck portion thereof, of a barrier device located within said stem and surrounding said cathode with its free end presenting a metal portion located within said stem and surrounding said cathode, said metal portion being out of electrical contact with said cathode and the side wall of said stem being free of interruptions and projecting parts whereby the continuity of said stem is unimpaired.
4. In an X-ray tube, the combination with its enclosing wall formed with a tubular extension forming the cathode stem, and a cathode located in said stem and extending at its head within the neck portion thereof, of a barrier device located within said stem and surrounding said cathode, said device being directly connected with a portion of the tube other than said enclosing wall with its free end presenting a metal portion located within said stem and surrounding said cathode, said metal portion being out of electrical contact with said cathode and the side wall of said stem being free of interruptions and projecting parts, whereby the continuity of said stem is unimpaired.
5. In an X-ray tube, the combination with its enclosing wall formed with a tubular extension forming the cathode stem, and a cathode located in said stem and extending at its head within the neck portion thereof, of a barrier device located within said stem and surrounding said cathode and supported from the end wall of said stem with its free end presenting a metal portion located within said stem and surrounding said cathode, and out of electrical contact with said cathode, whereby the side wall of said stem is free of interruptions and projecting parts and its continuity thus unimpaired.
6. In an X-ray tube, the combination with its enclosing wall formed with a tubular extension forming the cathode stem, a cathode support located within said stem and supported from the end wall of said stem, and a cathode on said support, the head of said cathode being within the neck portion of said stem, of a barrier device supported on said cathode support and located within said stem and surrounding said cathode with its free end presenting a metal portion located within said stem and surrounding said cathode, said metal portion being out of electrical contact with said cathode.
7. In an X-ray tube, the combination with its enclosing wall formed with a tubular extension forming the cathode stem, a cathode support within said stem, and a cathode on said support and within the neck portion of said stem, of a barrier device formed of a tubular member surrounding, and secured at one end to, said cathode support, with its free end presenting a metal portion located within said stem and surrounding said cathode, said metal portion being out of electrical contact with said cathode.
8. In an X-ray tube, the combination with its enclosing wall formed with a tubular extension forming the cathode stem, and a cathode located in said stem and extending at its head within the neck portion thereof, of a barrier device located within said stem and surrounding said cathode, the space between said cathode stem and the parts therein extending substantially to the outer end of said stem and open to the passage of gas thereto circulated by the operation of the tube, the wall of said barrier device extending substantially parallel with the surrounding portion of said enclosing wall for a distance greater than one-half the length of said extension.

In testimony whereof I have signed my name to this specification, this 3rd day of January, 1919.

OTTO A. ROENSCH.
